UNITED STATES PATENT OFFICE.

CHARLES E. HARTHAN, OF LYNN, MASSACHUSETTS, ASSIGNOR TO GENERAL ELECTRIC COMPANY, A CORPORATION OF NEW YORK.

ELECTRIC-ARC LAMP.

SPECIFICATION forming part of Letters Patent No. 730,369, dated June 9, 1903.

Application filed February 9, 1901. Serial No. 46,599. (No model.)

To all whom it may concern:

Be it known that I, CHARLES E. HARTHAN, a citizen of the United States, residing at Lynn, county of Essex, State of Massachusetts, have 5 invented certain new and useful Improvements in Electric-Arc Lamps, of which the following is a specification.

This invention relates to constant-current arc-lamps for direct-current series circuits.

10 Its object is to improve certain details of construction by which a greater efficiency is secured and the lamp is rendered more compact. To this end a compensating winding is used on the shunt-coils, and the rocker which 15 connects the armatures of the series and shunt magnets is made in two separate overlapping independently-pivoted parts connected so as to move simultaneously.

20 In the accompanying drawings, Figures 1 and 2 are elevations of the lamp mechanism, showing two positions of the rocker. Fig. 3 is a perspective view of the rocker on an enlarged scale. Fig. 4 is a sectional elevation of the shunt-coils and the starting resistance. 25 Fig. 5 is a perspective view of the cut-out. Fig. 6 is an elevation of the carbon-tube. Fig. 7 is a section of the same. Fig. 8 is a diagram of the circuits.

30 The frame of the lamp comprises the usual base-plate A, surmounted by a disk A', of insulation, on which is erected the tubular backbone B and from which depends the tilting table C. Hangers D for the lower carbon-support are attached to the plate A. 35 The upper end of the backbone fits into an opening in a top plate E and is screw-threaded to receive a nut b and washer b', by which it is secured. Inside the backbone slides the upper carbon-holder B', connected by a flexible conductor B² with a slit spring-plug B³, supported in the upper end of the backbone by a cross-bar b², having bent ends entering holes in the nut b.

40 The top plate E carries a number of binding-screws e for the several circuit-wires. A supporting-plate F is secured to the under side of the top plate E, being insulated therefrom, as by means of a mica sheet G.

A top cap H covers the upper end of the

lamp, being attached to studs f on the supporting-plate F. The top cap carries the insulated suspending-link H' and the line-terminal binding-posts II'. An inclosing casing K is suspended from screws h, inserted through the petticoat flange of the top cap. 50 55

Immediately under the supporting-plate are the series magnet L and the shunt-magnet M, each comprising two spools. The plate F supports two resistance-coils N N', each consisting of a tubular insulating-column n, helically grooved to receive the bare wire n' 60 and supported by a bolt n², passing through the plate F, the tubular column n, and washers n³ into a bearing-plate P. The series and shunt magnet spools are clamped between 65 the plates F and P, being symmetrically arranged on both sides of the backbone B. The clamping-bolts n² and the resistance-coils are preferably at the ends of the bearing-plate between the two magnets. The cores of the 70 magnets have conoidal, paraboloidal, or similar tapering ends l m coöperating with perforated armatures L' M'. Each armature is carried on a rocker-arm R or R', fulcrumed in suitable bearings in the bearing-plate P. 75 The bearings for the rocker-arm R are near the magnet M, while those for the rocker-arm R' are near the magnet L, so that the rocker-arms overlap. Each rocker-arm is U-shaped to straddle the backbone B, and one, 80 as R', has its arms wider apart to cross outside of the arms of the rocker-arm R, as clearly shown in Fig. 3. Attached to or integral with each rocker-arm is a rock-arm r r', 85 projecting in the same direction from the same end of the rocker-arms and having their outer ends connected by a pivoted link R². A downward movement of one armature causes an upward movement of the other, and vice versa. The length of each rocker-arm 90 is such that the arc described by the armature is flatter than would be possible if a single rocker of the walking-beam type were used with the magnets placed so near each other, as shown. The lamp is thus rendered more 95 compact without losing the advantage of a flat arc of movement for the armatures. Attached to one of the rocker-arms is an in-

verted dash-pot S, coöperating with a stationary plunger S', pivoted to an arm b^3 on the backbone B.

The upright clutch-rod T carries a bracket 5 T', swiveled thereon and having pivoted to it on a horizontal axis an insulated contact-block U, preferably having a beveled edge u to make bridging contact with two spring terminals V on a slab of insulation v, in circuit with the starting resistance N. The swiveling and pivotal movements give a universal joint action to the bridging contact, so that it comes to rest squarely on the terminals V V.

15 The circuits of the lamp are shown in the diagram Fig. 8. From the positive binding-post I runs a lead x, from which a branch 1 goes to the series coil L, another branch 2 to the starting resistance N, another branch 3 to the slide N² of the adjusting resistance N', and a fourth branch 4 to the compensating coils 5, wound in multiple on the spools of the shunt-magnet M. A wire 6 connects the series magnet with the shunt-magnet, and a 25 wire 7 connects the shunt-magnet with the lead y, running to the negative binding-post I'. The starting resistance is connected by wire 8 with one of the terminals V of the cut-out, the other terminal being connected 30 with the negative lead y by the wire 9. The adjusting resistance is connected with the upper carbon-holder, being thus in multiple with the series coil L. The compensating coils 5 are also in parallel with the series coil. 35 A switch W controls a short circuit 10 between the positive and negative binding-posts I I'. The current passing through the series coil can be regulated by moving the slide N² toward or away from the open end 40 of the resistance-coil N', thereby cutting in or out more resistance and increasing or diminishing the voltage at the arc. For variation in current of .2 of an ampere above or below a predetermined normal current for 45 which the lamp is originally adjusted no change in the adjusting resistance is necessary. For a greater difference the resistance can be altered, as above described. A decrease in the current flowing through the resistance-coil also increases that in the compensating coils, which being wound in the same direction as the shunt-coil serve to compensate for the increased resistance of the shunt-winding due to heat and the consequent cutting down of the current and loss 55 of magnetic strength, so as to maintain a differential balance between the shunt and series windings at any temperature.

It should be noted that when the series 60 armature drops it passes nearly out of the field of the series magnet. The object of this is to obviate the so-called "sneak feed" and insure a positive feed of the carbon by the shunt-magnet until the carbons are finally 65 permitted to drop together, when the shunt-magnets are weakened to such an extent that

the slight outlying field of the series magnet is able to attract the armature and reëstablish the arc, and thereby again set up the differential balance between the shunt and series windings.

What I claim as new, and desire to secure by Letters Patent of the United States, is—

1. In an arc-lamp, the combination with series and shunt magnets and feeding mechanism, of a lever system carrying the magnet-armatures made in two overlapping parts independently fulcrumed. 75

2. In an arc-lamp, the combination with series and shunt magnets and feeding mechanism, of a lever system carrying the magnet-armatures made in two parts overlapping each other and fulcrumed in separate bearings. 80

3. In an arc-lamp, the combination with series and shunt magnets and feeding mechanism, of a rocker system carrying the magnet-armatures made in two overlapping parts fulcrumed in separate bearings and pivotally connected together. 85

4. In an arc-lamp, the combination with series and shunt magnets and feeding mechanism, of a rocker-arm for each magnet fulcrumed near the other magnet, and pivotal connection between said arms to move them simultaneously. 90

5. In an arc-lamp, the combination with series and shunt magnets and feeding mechanism, of U-shaped rocker-arms crossing each other and pivotally connected. 95

6. In an arc-lamp, the combination with series and shunt magnets and feeding mechanism, of U-shaped rocker-arms crossing one inside the other and pivotally connected. 100

7. In an arc-lamp, the combination with series and shunt magnets and feeding mechanism, of U-shaped rocker-arms crossing each other, a rock-arm on each, and a link connecting the rock-arms. 105

8. In an arc-lamp, the combination with series and shunt magnets and feeding mechanism, of a bearing-plate on which said magnets are supported, rocker-arms fulcrumed on said plate near said magnets and crossing each other, and connected rock-arms on said rocker-arms. 110

9. In an arc-lamp, the combination with a backbone, of series and shunt magnets each comprising two spools all arranged symmetrically around said backbone, a bearing-plate on which said spools are mounted, U-shaped rocker-arms fulcrumed on said plate and crossing each other astraddle of the backbone, and a pivotal connection between said rocker-arms. 115

10. In an arc-lamp, the combination with a backbone, of a supporting-plate attached thereto, a bearing-plate below the supporting-plate, columns of insulation between said plates, bolts passing lengthwise through said columns, and magnet-spools clamped between said plates. 125

11. In an arc-lamp, the combination with

a backbone, of a supporting-plate attached thereto, a bearing-plate below the supporting-plate, columns of insulation between said plates, bolts passing lengthwise through said columns, magnet-spools clamped between said plates, and resistance-coils wound on said columns.

5 12. In an arc-lamp, the combination with series and shunt coils, of an adjusting resistance and compensating shunt-coils all in multiple with the series coil.

10 13. In an arc-lamp, the combination with series and shunt magnets, of compensating coils wound on the shunt-magnet spools in parallel with each other and with the series magnet, and an adjusting resistance also in parallel with the series magnet.

15 14. In an arc-lamp, the combination with

series and shunt magnets, having conoidal pole-pieces, of armatures connected to move 20 together and each adapted to drop nearly out of the field by a sharp change of magnetic flux when the other is attracted.

15. In an arc-lamp, the combination with series and shunt magnets and feeding mechanism, of levers carrying the magnet-armatures and overlapping to secure greater length of lever relative to the diameter of the lamp-casing.

In witness whereof I have hereunto set my 30 hand this 6th day of February, 1901.

CHARLES E. HARTHAN.
